REFRIGERATOR CONSTRUCTIONS

Edward M. Gaul, Evansville, Ind., assignor, by mesne assignments, to Whirlpool-Seeger Corporation, a corporation of Delaware

Application September 14, 1953, Serial No. 379,767

3 Claims. (Cl. 220—15)

This invention relates generally to refrigerator constructions, and more specifically to an improved breaker strip construction for a refrigerator cabinet.

As is well-known in the art, refrigerator breaker strip constructions require that means be provided for effectively and efficiently covering the space between the marginal edges of the inner and outer liners of a refrigerator cabinet. These means must be such as to prevent any substantial conduction of heat from the outer liner, through the means, to the inner liner of the refrigerator cabinet. Further, these means should be formed so as to present a pleasing appearance to the refrigerator cabinet, and additionally, these means should be as simple to install and remove, and as economical, as possible.

It is the object of this invention to provide a breaker strip construction which will fulfill all of the above noted requirements in an efficient manner.

It is a feature of this invention that a plurality of novel spring clips are used in cooperation with a particular breaker strip to maintain that breaker strip mounted to a particular refrigerator cabinet.

Other objects and features of the present invention will be apparent upon perusal of the following specification and drawing of which:

Figure 1 is a front plan view of a refrigerator cabinet constructed according to this invention;

Figure 2 is a partial cross sectional view of the refrigerator cabinet shown in Figure 1 and taken along the line 2—2.

The present embodiment is the preferred embodiment, but it is to be understood that changes can be made in the present embodiment by one skilled in the art without departing from the spirit and scope of this invention.

For a detailed description of this invention reference is made to the drawing. A refrigerator cabinet is provided which is generally constructed as any refrigerator cabinet well-known in the art. Wherein the structure of the refrigerator cabinet particularly departs from the structure well-known in the art, will be noted in detail below. As to the details of the general construction of the refrigerator cabinet, an outer liner 10, an inner liner 11, and a refrigerator door 12 are provided. The inner liner 11 is disposed within the outer liner 10 and is spaced some distance therefrom. Insulation 13 is positioned between the inner liner 11 and the outer liner 10 to prevent the conduction of heat from the outer liner to the inner liner 11. The outer marginal edges of the outer liner 10 and the inner liner 11 are formed to have a particular configuration which will be defined in detail below. Further, a machinery compartment 14 is generally provided within the lower portion of the outer liner 10 and below the inner liner 11. The refrigerator door 12 is pivotally mounted by means of the hinge structures 15 to the outer liner 10 along one vertical edge thereof. The refrigerator door 12 comprises an outer panel 16 and an inner panel 17. The outer panel 16 has a rolled edge extending about the outer marginal edges thereof as can be seen in Figure 2. The inner panel 17 is mounted to cooperate with

2

the outer panel 16 by means of the gasket and mounting means 18. The space between the inner panel 17 and the outer panel 16 of the refrigerator door 12 is filled with an insulating material 19, as is well-known in the art.

5 Any door latching means 20 is further provided and mounted to the refrigerator door 12 for cooperation with the refrigerator cabinet to permit latching and unlatching of the refrigerator door 12.

Turning next to a detailed description of the breaker strip construction, the outer marginal edges of the outer liner 10 are formed to have a rolled section, such as a yoder rolled section, whereby a substantially F-shaped flange is formed thereon when viewed in cross section as can easily be seen in Figure 2. The F-shaped flange comprises an outer leg 21 and an inner leg 22. This construction will form a substantially U-shaped channel about the marginal edges of the outer liner 10 and above the machinery compartment 14.

The outer marginal edges of the inner liner 11 are 20 formed to provide an outwardly extending flange 23 which may easily be seen in cross section in Figure 2. The flange 23 on the inner liner 11 is so formed as to lie substantially in the plane including the inner leg 22 of the F-shaped flange of the outer liner 10.

25 To structurally strengthen the refrigerator cabinet and to maintain the insulation 13 properly packed between the outer liner 10 and the inner liner 11, if the insulation 13 is not of a rigid type, a picture frame panel 24 is provided. The picture frame panel 24 must be formed of

30 a material having the property of low heat conductivity and good strength. Panel 24 may be formed of some material such as masonite. The inner and outer marginal edges of the panel 24 are respectively fastened to the flange 23 and the inner leg 22 of the F-shaped flange of

35 the outer liner 10. Any mounting means 25 well-known to the art may be used to fasten the inner edge of the panel 24 to the flange 23 of the inner liner 11. It is preferred that the outer marginal edge of the panel 24 be fastened to the inner leg 22 of the F-shaped flange of the

40 outer liner 10 by some means such as shown in Figure 2. This means comprises a plurality of fasteners, such as the fastener 26 shown in Figure 2, and a plurality of straps, such as the strap 27 shown in Figure 2. Each strap 27 and each fastener 26 are connected together through an

45 opening provided through the panel 24, and each of the straps 27 is so positioned that the inner leg 22 of the F-shaped flange of the outer liner 10 is sandwiched between a portion of the strap 27 and the panel 24, as can be seen in Figure 2. Each of the fasteners 26 and straps 27

50 are positioned in a spaced apart relation about the panel 24 to rigidly fasten the entire outer edge of the panel 24 to the inner leg 22 of the F-shaped flange of the outer liner 10.

Further, a breaker strip 28 is provided. The breaker strip 28 is formed in four longitudinal sections, one for each side of the refrigerator cabinet, and one for the top and one for the bottom of the refrigerator cabinet. The four sections of the breaker strip 28 may be formed of any material such as a molded plastic which

60 is a relatively poor conductor of heat, and the four sections of the breaker strip 28 are positioned about the space between the marginal edges of the outer liner 10 and the inner liner 11. The four sections of the breaker strip 28 may be joined at the ends thereof by any joining means 29 well-known in the art. The breaker strip 28 is somewhat U-shaped when viewed in a transverse cross section such as seen in Figure 2. One edge of the breaker strip 28 is positioned between the outer leg

65 21 and the inner leg 22 of the F-shaped flange of the outer liner 10, as can easily be seen in Figure 2. The other longitudinal edge of the breaker strip 28 is posi-

tioned to abut the outer surface of the flange 23 of the inner liner 11.

To properly maintain the breaker strip 28 in the afore-described position, and further, to permit easy removal of breaker strip 28 should access be desired to the space between the inner liner 11 and the outer liner 10, a plurality of spring clips, such as the spring clips 30 shown in Figures 1 and 2, are provided. Each of the spring clips 30 are formed of a material such as spring steel and are fashioned to be substantially G-shaped as can be seen in Figure 2. Each of the spring clips 30 is positioned within the U-shaped channel formed by the F-shaped flange of the outer liner 10 and in a spaced apart relationship to each other along the longitudinal edge of the breaker strip 28 which is positioned within the U-shaped channel of the outer liner 10. When each of these spring clips 30 is positioned as described above, each spring clip 30 is biased against the panel 24 at the point 30b and against the inner surface of the outer leg 21 of the F-shaped flange of the outer liner 10 at the point 30c. It is believed that this bias is stored within the portion 30d of the spring clip 30 when the spring clip 30 is projected into the U-shaped channel of the F-shaped flange of the outer liner 10. Further, when each of the spring clips 30 are positioned as described above, the portion 30a of each spring clip 30 is biased to grasp the longitudinal edge of the breaker strip 28. Each of the spring clips 30 are further biased about the point 30c to tend to rotate the breaker strip 28 in a counterclockwise direction about the point 31 as viewed in Figure 2.

Thus it may be seen that to remove any one of the four sections of the breaker strip 28 from the above described cooperation with the refrigerator cabinet, it is only necessary to draw the longitudinal edge of the breaker strip 28 and each one of the spring clips 30 mounted thereon from the U-shaped channel of the F-shaped flange of the outer liner 10. It can also be seen, that to properly mount any section of the breaker strip 28 in proper cooperation with the refrigerator cabinet, it is merely necessary to mount a plurality of spring clips 30 in a spaced apart relationship along the one longitudinal edge of the breaker strip 28, with the portions 30a of each of the spring clips 30 grasping that longitudinal edge of the breaker strip 28, and further, biasing each of the spring clips 30 and positioning the breaker strip 28 by projecting that longitudinal edge of the breaker strip 28 within the U-shaped channel of the F-shaped flange of the outer liner 10.

Having described the invention what is considered new and desired to be protected by Letters Patent is:

1. A breaker strip assembly for household refrigerators comprising an outer shell provided with a door opening at its forward end, said door opening being bordered by an inwardly open flange arrangement having a rectangular groove therein, a liner in said shell and having an outwardly turned flange located backwardly of the front of said shell, insulation between said liner and shell, and insulating means for supporting said liner from said shell, said flange arrangement including a face flange on the shell outwardly of said groove, a breaker strip comprising a member of uniform cross-section having a body adapted to traverse the space between the grooved shell and liner, said body having an inwardly extending flange on its inner side, said flange having its edge engaging the outwardly turned flange on the liner, said body also engaging behind said face flange and having an inwardly turned edge flange in said groove and a plurality of spring clips engaging over said edge,

each spring clip having a U-shaped formation which clamps said edge and an integral C-shaped formation which is compressed between the rear of the face flange and said insulating means and tending to retain said breaker strip in said groove.

2. A breaker strip assembly for household refrigerators comprising an outer shell provided with a door opening at its forward end, said door opening being bordered by an inwardly open flange arrangement having a rectangular groove therein, a liner in said shell and having an outwardly turned flange located backwardly of the front of said shell, insulation between said liner and shell, and insulating means for supporting said liner from said shell, said flange arrangement including a face flange on the shell outwardly of said groove, a breaker strip comprising a member of uniform cross-section having a body adapted to traverse the space between the grooved shell and liner, said body having an inwardly extending flange on its inner side, said flange having its edge engaging the outwardly turned flange on the liner, said body also engaging behind said face flange and having an inwardly turned side flange in said groove and a plurality of spring clips engaging over said edge, each spring clip having a U-shaped formation which clamps said edge and an integral C-shaped formation which is compressed between the rear of the face flange and said insulating means and tending to retain said breaker strip in said groove, said C-shaped formation also having its U-shaped formation so located that it draws said edge toward the rear of said face flange exerting a pivotal action at the engagement of the body and rear of the face flange which holds the other end of the breaker strip in engagement with the liner flange.

3. A breaker strip assembly for household refrigerators comprising an outer shell provided with a door opening at its forward end, said door opening being bordered by an inwardly open flange arrangement having a rectangular groove therein, a liner in said shell and having an outwardly turned flange located backwardly of the front of said shell, insulation between said liner and shell, and insulating means for supporting said liner from said shell, said flange arrangement including a face flange on the shell outwardly of said groove, a breaker strip comprising a member of uniform cross-section having a body adapted to traverse the space between the grooved shell and liner, said body having an inwardly extending flange on its inner side, said flange having its edge engaging the outwardly turned flange on the liner, said body also engaging behind said face flange and having an inwardly turned edge flange in said groove, and a plurality of spring clips engaging over said edge, each spring clip having a U-shaped formation which clamps said edge and an integral C-shaped formation which is compressed between the rear of the face flange and said insulating means and tending to retain said breaker strip in said groove, the said insulating means comprising an integral frame of rigid insulating material secured to said shell and to said liner for closing the space in front of the insulation and effecting a rigid support of the liner.
